CLAIM

The ornamental design for a filament box, as shown and described.

DESCRIPTION

FIG. 1 is a front, top, and right perspective view of a filament box showing the new design;

FIG. 2 is a front elevation view of the filament box of FIG. 1;

FIG. 3 is a right side elevation view of the filament box of FIG. 1;

FIG. 4 is a back side elevation view of the filament box of FIG. 1; and

FIG. 5 is a left side elevation view of the filament box of FIG. 1;

FIG. 6 is a top plan view of the filament box of FIG. 1; and, FIG. 7 is a bottom plan view of the filament box of FIG. 1. The broken lines shown represent portions of the filament box that form no part of the claimed design.
